United States Patent Office

Des. 203,668
Patented Feb. 8, 1966

203,668

LOADER VEHICLE

Eddie B. Wagner, Portland, Oreg., assignor to Wagner Manufacturing, Inc., Portland, Oreg., a corporation of Oregon

Filed May 20, 1965, Ser. No. 85,380

Term of patent 14 years

(Cl. D14—3)

Des. 203,668

PAGE 2

FIGURE 1 is a view of the right side of a loader vehicle with the bucket in carrying position, showing my design;

FIGURE 2 is a view of the left side of the vehicle with the bucket in dumping position;

FIGURE 3 is a top plan view with the vehicle in turning position and the bucket in carrying position;

FIGURE 4 is a perspective view of the motor end of the vehicle; and

FIGURE 5 is an end view showing the bucket end of the vehicle.

I claim:

The ornamental design for a loader vehicle, as shown.
